UNITED STATES PATENT OFFICE.

ARTHUR BATES, OF LEICESTER, ENGLAND, ASSIGNOR, BY MESNE ASSIGNMENTS, TO
UNITED SHOE MACHINERY CORPORATION, OF PATERSON, NEW JERSEY, A COR-
PORATION OF NEW JERSEY.

MACHINE FOR INSERTING FASTENINGS.

1,398,293.

Specification of Letters Patent. Patented Nov. 29, 1921.

Application filed June 14, 1917. Serial No. 174,742.

To all whom it may concern:

Be it known that I, ARTHUR BATES, a subject of the King of England, residing at Leicester, Leicestershire, England, have invented certain Improvements in Machines for Inserting Fastenings, of which the following description, in connection with the accompanying drawings, is a specification, like reference characters on the drawings 10 indicating like parts in the several figures.

This invention relates to machines for inserting fastenings, and the general object of the invention is to provide an improved machine of this class especially adapted for 15 use in the manufacture of boots and shoes.

The illustrated embodiment of the invention is designed with especial reference to adaptability for securing uppers to the soles of shoes of the type known as clogs 20 by inserting individual metallic fastenings through the marginal portion of the upper to secure the upper permanently to the sole.

The invention is herein shown as embodied 25 in a machine adapted to insert successively previously formed headed fastenings, such machines being commonly known as loose nailing machines. The adaptability of the invention as a whole or in part to fastening inserting machines of other types and to 30 uses other than the particular use above set forth is, however, recognized.

A particular object of this invention is to provide an improved shoe feeding and guiding mechanism which, without sacrifice of 35 other utility, will be adapted to be incorporated in a machine of the type above mentioned and which will be especially adapted for use in performing the operation of securing the uppers of clogs to the soles there- 40 of, to the end that a machine may be provided by the use of which boots and shoes of certain types, including particularly clogs, may be manufactured more economic- 45 ally and with greater facility.

With these objects in view, the illustrated machine has incorporated therein work feeding and guiding means comprising a shoe upper engaging abutment and a shoe feed foot organized relatively to each other and 50 to the fastening inserting mechanism of the machine to cause fastenings to be inserted through the margin of the upper of a clog or other shoe and into a groove in the edge of the shoe sole to secure the upper per-

manently to the sole, the feed foot operating 55 periodically by engagement with the shoe upper in the line of fastening insertion to feed the shoe between successive fastening inserting operations, and the abutment comprising a blade or finger against which the 60 shoe is pressed and which is adapted to engage the upper and press it into the groove in the sole.

In accordance with other features of the invention, the shoe feed foot, which is normally out of engagement with the shoe, is brought periodically into engagement with the shoe upper in the groove in the sole and caused to thrust the shoe out of operative engagement with the abutment, and there- 70 after to impart lateral feeding movement to the shoe between successive fastening insertions.

A further feature consists in the relative construction and arrangement of the throat 75 through which the fastenings are driven and the above-mentioned abutment, whereby provision is made to prevent trapping the upper materials between the abutment and the throat as the shoe is advanced for the 80 insertion of successive fastenings.

In order to insure that the fastenings do not protrude into the inside of the shoe, an auxiliary abutment is provided which is constructed and arranged relatively to the 85 work feeding and guiding members above mentioned and relatively to the fastening inserting mechanism to determine the angular relation of the parts of the shoe to be operated upon to the fastening inserting 90 mechanism so as to determine the angular relation of the nails to the general plane of the sole, and particularly to determine the angular relation of the nails to the general plane of the face of the sole nearest the nail 95 locations.

Other objects and features of the invention will be apparent from the following detailed description read in connection with the drawings.

The invention will be described as applied to a loose nailing machine of the type disclosed in United States Letters Patent No. 490,624, granted January 24, 1893, on an application of Louis Goddu, to which Letters 105 Patent reference may be had for a detailed description and explanation of various features of the illustrated machine not set

forth fully herein. It is to be understood that the invention is not limited to use in connection with machines of the type disclosed in said Letters Patent since the applicability of the invention to other types of fastening inserting machines employing individual metallic fastenings, including machines of other types employing previously formed fastenings, is recognized.

10 In the following description the term "nail" will sometimes be used instead of "fastening" in describing the various mechanisms and the various operations performed by the machine, such use of the term "nail" being simply for convenience and not by way of limitation.

Referring to the drawings,

Figure 1 is a front view of the upper part of a machine of the type aforesaid having 20 incorporated therein a preferred embodiment of the present invention;

Fig. 2 is an angular perspective illustrating the relative location and arrangement of the principal operating instrumentalities of 25 the machine;

Figs. 3, 4, 5 and 6 are fragmentary details in elevation illustrating the relative location and arrangement of the fastening inserting driver and the work guiding and feeding 30 parts at different stages in the cycle of operations of the machine; and

Fig. 7 is an elevation illustrating one way in which it is contemplated that the invention may be utilized.

35 The illustrated machine, like the machine shown in said Letters Patent, is of the type in which the principal operating instrumentalities are carried by a swinging head which is operated periodically between successive 40 fastening inserting operations of the machine to effect lateral shoe feeding movements through the instrumentality of shoe feeding means to be hereinafter described. The fastening inserting mechanism comprises a reciprocating driver operating in a nail passage in a fastening receiving throat. For supplying fastenings to the fastening inserting mechanism, the machine is provided with a raceway adapted to receive previously 45 formed headed nails from a hopper, and separator mechanism for governing the supply of nails from the raceway to the fastening inserting mechanism, the separator operating periodically to separate the endmost nail from the line of nails in the raceway and then to present that nail in position for the operation of the driver. For a complete disclosure and description of the construction and operation of the before-mentioned 55 parts and their operating mechanisms reference should be had to said prior Letters Patent since conveniently and as shown these parts may be substantially like corresponding parts of the machine shown in said 60 Letters Patent.

Referring to the drawings, the illustrated machine has a supporting frame comprising a base, a standard or column 2 and a stationary head or frame upon which is pivoted a swinging head indicated at 4. In the head 4 70 are mounted the various parts of the fastening supplying, separator, fastening inserting, and shoe guiding and feeding mechanisms.

Mounted in a guideway in the swinging 75 head 4 is a driver bar 6 carrying a fastening inserting driver 8. For reciprocating the driver bar 6, the upper end of the driver bar is connected by a ball joint to a link 10 (Fig. 1) in turn connected to a lever 12. 80 When permitted, a spring 14 operates through the lever 12 to force the driver bar 6 downwardly, the driver bar 6 being lifted against the tension of the driving spring 14 by a cam, indicated at 16, carried on the 85 front end of the main driving shaft and operated in the rotation of said shaft to engage a block 18 projecting from the driver bar 6. Said driving shaft is driven from a loose pulley which may be clutched to the shaft at 90 the will of the operator by suitable clutch mechanism. The driver 6 is received in a suitable driver guide 20 and operates in a nail passage in a throat 22 to drive nails successively through said throat and into the 95 work.

For supplying nails to the fastening inserting mechanism, the machine is provided with a raceway 24 adapted to receive previously 100 formed headed nails from a hopper (not shown) and down which the nails gravitate to the lower end of the raceway.

Adjacent to the lower end of the raceway 24 is a separator 26. The separator 26 is carried at the lower end of a lever 105 28 fulcrumed on the swinging head 4 at 30 and provided at its upper end with a roller, indicated at 32, which bears against a cam face forming part of the cam disk 16. A suitable strong spring 34 attached to the 110 swinging head 4 operates to maintain the roller 30 in engagement with its operating cam. As shown, the separator 26 and its operating mechanism are of well-known construction and as fully described in said Letters Patent and need not be described in detail herein, the construction and arrangement providing for reciprocating the separator periodically to cause its blade end to be inserted between the endmost nail of the 115 line of nails in the raceway 24 and the adjacent nail and to move said endmost nail to present it for the operation of the driver.

In accordance with the present invention, the illustrated machine is provided with 125 novel shoe guiding and feeding means especially organized relatively to the fastening inserting mechanism to cause fastenings to be inserted through the margin of the upper of a boot or shoe and into the shoe 130

sole to secure the upper permanently to the shoe sole and operating to feed the work between successive fastening insertions by engagement with the shoe upper in the line of 5 fastening insertion.

The embodiment of the invention herein shown and described is especially intended and adapted for permanently attaching uppers to the soles of clogs of the type sometimes called "Baltic" clogs, that is, clogs 10 commonly comprising a wooden sole over which the upper is lasted so that the margin overlies the upstanding edge of the sole to which it is secured by fastenings, in the illustrated case previously formed headed fastenings of the type known as loose nails. As 15 shown, the sole 36 (Fig. 7) of the clog has its upstanding edge 38 grooved, as indicated at 40, the upper 42 being forced into the grooved 40 and permanently fastened in that location by successive nails 44. It will 20 be understood, however, that description of applicant's novel mechanism with especial reference to its application to use in the manufacture of this particular type of shoes 25 is not intended to be restrictive of the invention.

The illustrated machine is provided with a shoe locating abutment comprising a depending tapered blade or finger 46 adjustably fixed to the stationary head frame of the machine with its lower and operative end 48 located adjacent to the normal position of the throat 22 on the rearward side 30 of it in the direction of feed. As is best shown in Figs. 3 to 6, inclusive, the end 48 of the abutment member 46 is a little lower than the lower face of the throat 22 so that when the operator presses the clog up 35 against the finger or guide 46 in the manner illustrated in Fig. 7, the general plane of the clog sole being more or less vertical, the member 46 will enter the groove 40 in the edge of the clog sole and will fit into the angle of the upper which corresponds substantially with the angle of the groove and 40 press the upper into the groove of the sole. Consequently, so long as the operator holds the work up to it, the abutment 46 will 45 locate the upper and the sole to be operated on both vertically as to height and horizontally as to lateral position for the action 50 of the work feeding and fastening inserting instrumentalities.

55 For feeding the shoe between successive fastening inserting operations, the machine of the drawings is provided with a feed foot 50 serrated at its lower end, as indicated at 52, to insure effective gripping action 60 on the upper during its feeding movement, the feed foot 50 being adapted to be brought periodically into engagement with the shoe upper in the groove 40 and then being operated to impart lateral feeding movement to 65 the shoe by such engagement with the shoe

upper. The abutment member 46 is preferably so adjusted as to aline its end 48 with the feed foot 50 in the direction of feed of the work so that both the abutment member 46 and the feed foot 50 may engage 70 the upper in the angle of the groove of the clog sole whereby they are enabled to perform their respective operations most effectively.

The feed foot 50 is carried by a bar 54 75 which corresponds in the illustrated machine to the awl bar of the machine shown in said Letters Patent, the bar 54 and the depending feed foot 50 having imparted to them vertical movements into and out of 80 operative relation to the shoe and lateral shoe feeding movements by mechanism which, as shown, is substantially like the mechanism by which the work penetrating 85 and shoe feeding movements are imparted to the awl bar and awl of the machine of said Letters Patent.

For imparting vertical reciprocating movements to the shoe feeding member 50, the bar 54 is provided with a rack, indicated 90 at 56 (Fig. 1) which is engaged by teeth on the front end of a toothed segment lever 58 carried at the outer end of a cam-operated rock shaft, indicated at 60, carried in the swinging head 4, the bar 54 being mounted 95 for vertical reciprocation in the said swinging head. Lateral swinging movement is imparted to the head 4 to effect shoe feeding movement of the bar 54 and shoe feed foot 50 by a cam-operated rock shaft and 100 connections fully described in said prior Letters Patent. To accommodate the feed foot 50, the throat piece 22 has a suitably shaped feed foot guiding slot 62 (Fig. 2).

In the normal positions of the parts, the lower and serrated end 52 of the feed foot 50 is slightly above the lower end 48 of the abutment 46 against which the shoe upper in the groove 40 in the shoe sole 36 is pressed. During the operation of the machine the feed foot 50 is lowered by its above-described operating mechanism to engage the upper in the groove 40 and to thrust the shoe out of engagement with the abutment 46 (Fig. 3), the driver 8 being lifted 110 preparatory to a driving stroke (Fig. 4). The feed foot 50 is then moved laterally into the position shown in Fig. 5 to effect shoe feeding movement by its engagement with the upper in the line of fastening insertion 115 upon swinging movement of the head 4. Thereafter the feed foot 50 rises, the work being once more pressed against the lower end 48 of the abutment 46 and the feed foot 50 returning laterally upon swinging movement of the head 4 to place the throat 22 and the nail therein in the line of drive. The driver 8 is then forced downwardly to drive the nail which has just been delivered 125 into the nail throat 22 through the nail 130

passage in the said throat and through the shoe upper into the said groove in the edge of the sole. Preferably the driver 8 is so set in its driver bar 6 that its lower end 5 reaches well below the lower end 48 of the abutment 46 at its lower limit of movement to cause the heads of the nails to be driven well into the upper 42.

To determine the angular relation of the 10 shoe to the abutment 46 and the driver 8 so as to cause the fastenings to be inserted into the sole in predetermined relation to the general plane of the sole or a face of the sole to insure that the nails shall not 15 protrude into the inside of the clog, an auxiliary abutment, comprising an angle gage or stud 64, is provided. This auxiliary abutment, as shown, is a fixed horizontally disposed blade located on the side 20 of the throat 22 away from the operator and spaced a little from said throat. The lower and operative surface of the member 64 is located somewhat below the level of the lower end 48 of the guide 46 and bears 25 on the edge 38 of the clog sole in such manner that it is thereby caused to assume a substantial angle to the horizontal. As a result the nails, as indicated in Fig. 7, are driven at a substantial angle to the general 30 plane of the adjacent face of the sole. Preferably the gage 64 is adjustable to vary the angle as desired.

In accordance with a further feature of the invention, the lower right hand corner 35 66 of the throat 22, looking at Figs. 3 to 6, that is, the lower corner nearest the abutment 46, is somewhat rounded off, and the lower surface of the throat 22 is somewhat inclined upwardly from left to right, as indicated at 68, to insure that the upper materials, particularly around the curved toe and heel portions of the shoe, will not be 40 trapped between the end portion 48 of the abutment 46 and the throat 22 on the return 45 movement of the throat 22 after a shoe feeding movement.

Having fully described my invention, what I claim as new and desire to secure by United States Letters Patent is:

50 1. In a machine of the class described, mechanism for inserting individual metallic fastenings comprising a throat, mechanism for supplying fastenings to said throat, and work guiding and feeding means comprising a shoe upper engaging abutment and a shoe feed foot arranged substantially in alinement with each other in the direction of the feed of the work, said work guiding and feeding means being organized relatively to 55 said throat to facilitate the insertion of fastenings in the upper of a boot or shoe in position to secure the upper to the shoe sole, and said feed foot operating to feed the work 60 between successive fastening insertions by 65 engagement with the shoe upper.

2. In a machine of the class described, mechanism for inserting individual metallic fastenings, mechanism for supplying fastenings to said inserting mechanism, and work guiding and feeding means comprising 70 a shoe feed foot and a shoe locating abutment arranged substantially in alinement with said foot and positioned rearwardly of the feed foot in the direction of the feed of the work, said work feeding and 75 guiding members being constructed and arranged relatively to each other and to said inserting mechanism to facilitate the insertion of fastenings through the margin of the upper of a boot or shoe and into the shoe 80 sole to secure the upper to the shoe sole, and said feed foot operating to feed the work between successive fastening insertions by engagement with the shoe upper in the line of fastening insertion. 85

3. In a machine of the class described, in combination, mechanism for inserting individual metallic fastenings, mechanism for supplying fastenings to said inserting mechanism, work guiding means comprising a 90 shoe locating abutment spaced from the fastening inserting mechanism and arranged substantially in alinement with the fastening inserting mechanism in the direction of the feed of the work, and work feeding means, 95 said fastening inserting mechanism, work feeding means, and work guiding means being organized to facilitate the insertion of fastenings through the margin of the upper of a boot or shoe and into the upstanding 100 edge of the shoe sole in such a manner as to secure the upper permanently to the shoe sole, and said work feeding means operating to feed the work between successive fastening insertions. 105

4. In a machine of the class described, in combination, mechanism for inserting individual previously formed headed fastenings successively in a boot or shoe, raceway mechanism for supplying fastenings to the 110 fastening inserting mechanism, separator mechanism for governing the supply of fastenings from the raceway mechanism, work guiding means comprising a shoe locating abutment constructed and arranged to present a work guiding surface substantially in alinement with the fastening inserting mechanism in the direction of the feed of the work to facilitate the insertion of fastenings through the upper in position to secure the 115 upper to the shoe sole, and work feeding means operating to feed the work between successive fastening insertions. 120

5. In a machine of the class described, mechanism for inserting individual metallic 125 fastenings successively in the upper of a boot or shoe to secure the upper to the shoe sole, mechanism for supplying fastenings to the fastening inserting mechanism, and work guiding and feeding mechanism com- 130

- prising a shoe upper engaging abutment to locate the shoe during the insertion of fastenings, a feed foot interposed between the abutment and the fastening inserting mechanism and normally out of engagement with the shoe, and means for operating said feed foot constructed and arranged to thrust the shoe periodically out of engagement with said abutment and thereafter to impart lateral feeding movement to the shoe between successive fastening inserting operations by engagement with the shoe upper.
6. In a machine of the class described, in combination, mechanism for inserting individual metallic fastenings comprising a movable head and a driver carried by said head and movable into and out of the line of drive by operation of said head, mechanism for supplying fastenings to the fastening inserting mechanism, and work guiding and feeding mechanism comprising a shoe upper engaging abutment against which the shoe is pressed to locate it for the insertion of fastenings, said head and said abutment being relatively movable, a feed foot normally out of engagement with the shoe and movable with said head, and means for operating said feed foot constructed and arranged to thrust the shoe periodically out of engagement with said abutment by engagement of said feed foot with the shoe upper and thereafter to impart lateral feeding movement to the shoe between successive fastening inserting operations, said work feeding and guiding mechanism being organized so to present the shoe to the fastening inserting mechanism as to cause the successive fastenings to be inserted through the shoe upper in position to secure the upper to the shoe sole.
7. In a metallic fastening inserting machine, mechanism for inserting individual metallic fastenings, mechanism for supplying fastenings to said inserting mechanism, and work guiding means comprising a shoe upper engaging abutment separate from the fastening inserting mechanism and constructed and arranged to locate the shoe for the insertion of fastenings by engagement in a groove formed in the sole, and a serrated feed foot operating periodically to feed the work between successive fastening insertions.
8. In a metallic fastening inserting machine, mechanism for inserting individual metallic fastenings, mechanism for supplying fastenings to said inserting mechanism, and work guiding and feeding means comprising a shoe upper engaging abutment constructed and arranged to locate the shoe for the insertion of fastenings by engagement in a groove formed in the sole, and a feed foot operating periodically between successive fastening insertions to impart lateral feeding movement to the shoe by en-
- gagement with the shoe upper in said groove, said abutment being positioned rearwardly of the feed foot in the direction of the feed of the work and operating to press successive portions of the margin of the upper into the groove prior to the operation of the feed foot and fastening inserting mechanism.
9. In a metallic fastening inserting machine, mechanism for inserting individual metallic fastenings, mechanism for supplying fastenings to said inserting mechanism, and work guiding and feeding means comprising a blade or finger spaced from the fastening inserting mechanism and constructed and arranged to locate the shoe by engagement with the upper of the shoe in a groove in the shoe sole to cause successive fastenings to be inserted in said groove to secure the upper to the shoe sole, and work feeding means operating periodically to impart lateral feeding movement to the shoe between successive fastening insertions.
10. In a metallic fastening inserting machine, means for supplying individual metallic fastenings, mechanism for inserting said fastenings successively through the upper of a boot or shoe to secure the upper permanently in a groove in the shoe sole, said mechanism comprising a movable head and a driver carried by said head and movable into and out of the line of drive by movement of said head, and work feeding means carried by said head and comprising a serrated feed foot adapted to press the upper into said groove and to impart lateral feeding movements to the shoe between successive fastening insertions by such engagement with the upper.
11. In a metallic fastening inserting machine, means for supplying previously formed fastenings, mechanism for inserting said fastenings successively through the upper of a boot or shoe to secure the upper permanently in a groove in the upstanding edge of the shoe sole, and work guiding and feeding means comprising a shoe locating abutment spaced from said fastening inserting mechanism and adapted to press the upper into said groove in the sole against which abutment the shoe is thrust to locate it for the insertion of fastenings, and work feeding means adapted to impart lateral feeding movements to the shoe between successive fastening insertions.
12. A metallic fastening inserting machine for permanently securing the uppers of wooden soled clogs comprising means for supplying previously formed fastenings, mechanism for inserting said fastenings successively through the upper of a clog to secure the upper permanently to the sole of the clog, and work guiding and feeding means comprising an abutment adapted to press the upper into said groove, and a ser-

rated feed foot interposed between the abutment and the fastening inserting mechanism and operating by engagement with the upper in said groove to impart lateral feeding movements to the clog between successive fastening insertions.

13. In a metallic fastening inserting machine, fastening inserting mechanism comprising a throat-piece and work guiding means comprising an abutment adapted to engage the upper of a shoe and presenting a surface inclined in the direction of the feed of the work and arranged to press successive portions of the upper into a groove in the sole of the shoe prior to the operation of the fastening inserting mechanism thereon, and means for imparting lateral feeding movements to the shoe between successive operations of the machine.

14. In a metallic fastening inserting machine, means for supplying individual metallic fastenings, fastening inserting mechanism comprising a driver and a throat, work guiding means comprising a shoe engaging abutment adjacent to said throat, and operating means for said fastening inserting mechanism comprising means for moving said throat relatively to said abutment, said throat having its under side beveled upwardly toward said abutment to prevent trapping the upper between the throat and the abutment upon relative movement of said parts.

15. In a fastening inserting machine, means for supplying individual metallic fastenings, mechanism for inserting said fastenings comprising a driver and operating mechanism therefor, a shoe guiding abutment against which the margin of a shoe upper overlying the upstanding edge of the shoe sole is thrust, and an auxiliary shoe guiding member adapted by engagement with said edge of the shoe sole to define the angular relation of the shoe to said first-named abutment and said fastening inserting driver so as to cause the fastenings to be inserted through the upper into the sole in a predetermined relation to the general plane of a face of the sole.

16. In a machine of the class described, mechanism for inserting fastenings successively for attaching the margin of an upper in a groove formed in an outsole, in combination with a locating abutment spaced from the fastening inserting mechanism and constructed and arranged to press successive portions of the margin of the upper in the groove of the outsole prior to the operation of the fastening inserting mechanism thereon and operating to position the work relatively to the fastening inserting mechanism.

17. In a machine of the class described, mechanism for inserting fastenings for attaching the margin of an upper in the groove

of an outsole, said mechanism comprising a throat piece shaped to engage in said groove, in combination with guiding means for the work spaced from the throat piece and arranged in substantial alinement with the throat piece, said guiding means being constructed to engage in the groove of the outsole and to press successive portions of the margin of the upper into the groove prior to operation of the fastening inserting mechanism thereon.

18. In a machine of the class described, mechanism for inserting fastenings, work guiding means constructed and arranged to present a work guiding surface arranged substantially in alinement with the fastening inserting mechanism in the direction of the feed of the work, means for moving the fastening inserting mechanism in the line of feed toward and from the guiding means, and means operable to feed the work upon movement of the fastening inserting mechanism away from the guiding means.

19. In a machine of the class described, the combination with fastening inserting mechanism for securing the margin of an upper in the groove of an outsole, and a four-motion feed foot arranged to feed the work relatively to the fastening inserting mechanism, of work guiding means constructed and arranged for engagement in the groove of the outsole for guiding the outsole as it is held against said work guiding means and fed relatively to said fastening inserting mechanism in the attachment of the upper thereto.

20. In a machine of the class described, a frame, fastening inserting mechanism mounted on said frame, and a work positioning member fixed to said frame in spaced relation to the fastening inserting mechanism and presenting an elongated work guiding portion arranged substantially in the plane of operation of the fastening inserting mechanism on the work.

21. In a machine of the class described, mechanism for operating on a shoe, means for feeding the shoe, and a shoe positioning member elongated in the direction of feed of the shoe and disposed at one side of the operating mechanism in substantial alinement with the point of operation of the operating mechanism on the shoe.

22. In a machine of the class described, mechanism for inserting fastenings for attaching the margin of an upper in the groove of an outsole, means for feeding the work relatively to the fastening inserting mechanism constructed and arranged for engagement in the groove of the outsole, and work guiding means operating to press successive portions of the margin of the upper in the groove of the outsole prior to the operation of the feeding means and the fastening inserting mechanism thereon.

23. In a machine of the class described, mechanism for inserting fastenings for attaching the margin of an upper in the groove of an outsole, means for feeding the work relatively to the fastening inserting mechanism, work guiding means, said fastening inserting mechanism and said guiding means being positioned on opposite sides of said feeding means and constructed and arranged to engage in the groove of the outsole thereby to locate the work relatively to the feeding means.
24. In a machine of the class described, fastening inserting mechanism for securing the margin of an upper in the groove of an outsole comprising means for feeding the work, and means mounted rearwardly of the feeding means in the direction of feed of the work for guiding the work by engagement in said groove.
25. In a machine of the class described, fastening inserting mechanism for securing the margin of an upper in the groove of a sole and a blade spaced rearwardly from the fastening inserting mechanism in the direction of movement of the work past the fastening inserting mechanism and formed to present a surface inclined in the direction of movement of the work so as to press the upper into the groove of the sole prior to the operation of the fastening inserting mechanism thereon.
26. In a machine of the class described, fastening inserting means for securing the margin of an upper to a sole, a guide formed to press the upper against the sole as the work is fed there past, and a feed member mounted between the fastening inserting means and the guide and operating to feed the work to the fastening inserting means.
27. In a machine of the class described, fastening inserting means for securing the margin of the upper to a sole, a guide arranged for engagement with the upper, and a feed foot mounted between the fastening inserting means and the guide and operating to feed the work to the fastening inserting means.

In testimony whereof I have signed my name to this specification.

ARTHUR BATES.
